(57) **CLAIM**

The ornamental design for a photographable digital aiming device, as shown and described.

DESCRIPTION

FIG. 1 is a perspective view of a photographable digital aiming device;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front view of the device mounted on a gun, the broken line forming the gun portion of the design that forms no part of the claim.
